Primary Examiner — Samantha Q Lawrence*Assistant Examiner* — Holly M Rodriguez(74) *Attorney, Agent, or Firm* — Hamre, Schumann, Mueller & Larson, P.C.(57) **CLAIM**

The ornamental design for a laser lancing device, as shown and described.

DESCRIPTIONFIG. 1 is a perspective view of a laser lancing device showing our new design,
FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and

FIG. 8 is a perspective view thereof shown with additional environment; and,
FIG. 9 is an enlarged view of an end of the laser lancing device of FIG. 1.

The broken line representations in the figures show unclaimed environment, and thus form no part of the claimed design.

The broken line areas show portions of the laser lancing device that form no part of the claimed design.
